The ornamental design for blank foldable to form a handheld
jig for guiding driving of a fastener or tool, as shown and
described.

DESCRIPTION

This application is related to the following commonly
owned co-pending patent application: U.S. application Ser.
No. 29/758,307, entitled "Handheld Jig for Guiding Driving
of a Fastener or Tool".

FIG. 1 is a front view of a blank foldable to form a handheld
jig for guiding driving of a fastener or tool of my new
design.

FIG. 2 is rear view of the blank of FIG. 1.

FIG. 3 is an end elevation view of the blank of FIG. 1, the
opposite end elevation view being a mirror image thereof.
FIG. 4 is a side elevation view of the blank of FIG. 1, the
opposite side elevation view being a mirror image thereof.
FIG. 5 is a front upper left perspective view of the blank of
FIG. 1.

FIG. 6 is a front upper right perspective view of the blank of
FIG. 1.

FIG. 7 is a front lower left perspective view of the blank of
FIG. 1.

FIG. 8 is a front lower right perspective view of the blank of
FIG. 1.

FIG. 9 is a rear upper right perspective view of the blank of
FIG. 1.

FIG. 10 is a rear upper left perspective view of the blank of
FIG. 1.

FIG. 11 is a rear lower right perspective view of the blank of
FIG. 1.

FIG. 12 is a rear lower left perspective view of the blank of
FIG. 1.

FIG. 13 is a perspective view of the blank of FIG. 1 folded
to form the jig; and,

(Continued)

FIG. 14 is a perspective view of the blank of FIG. 1 folded to form another jig that is oppositely handed to the jig shown in FIG. 13.
